(57) **CLAIM**

The ornamental design for an ice mold, as shown and described.

DESCRIPTION

FIG. 1 is a perspective view of an ice mold including a first embodiment of the ornamental design, showing the ice mold in a closed condition.

FIG. 2 is a front elevational view of the ice mold of FIG. 1. FIG. 3 is a rear elevational view of the ice mold of FIG. 1. FIG. 4 is a left side elevational view of the ice mold of FIG. 1.

FIG. 5 is a right side elevational view of the ice mold of FIG. 1.

FIG. 6 is a top end view of the ice mold of FIG. 1.

FIG. 7 is a bottom end view of the ice mold of FIG. 1.

FIG. 8 is a perspective view similar to FIG. 1 showing the ice mold in an open condition.

FIG. 9 is a front elevational view of the ice mold of FIG. 8.

FIG. 10 is a rear elevational view of the ice mold of FIG. 8.

FIG. 12 is a left side elevational view of the ice mold of FIG. 8.

FIG. 13 is a top end view of the ice mold of FIG. 8.

FIG. 14 is a bottom end view of the ice mold of FIG. 8.

FIG. 15 is a perspective view of an ice mold including a second embodiment of the ornamental design, showing the ice mold in a closed condition.

FIG. 16 is a front elevational view of the ice mold of FIG. 15.

FIG. 17 is a rear elevational view of the ice mold of FIG. 15. FIG. 18 is a left side elevational view of the ice mold of FIG. 15.

FIG. 19 is a right side elevational view of the ice mold of FIG. 15.

FIG. 20 is a top end view of the ice mold of FIG. 15.

FIG. 21 is a bottom end view of the ice mold of FIG. 15.

FIG. 22 is a perspective view similar to FIG. 15 showing the ice mold in an open condition.

FIG. 23 is a front elevational view of the ice mold of FIG. 22.

FIG. 24 is a rear elevational view of the ice mold of FIG. 22.

FIG. 25 is a left side elevational view of the ice mold of FIG. 22.

(Continued)

FIG. 26 is a right side elevational view of the ice mold of FIG. 22.

FIG. 27 is a top end view of the ice mold of FIG. 22; and, FIG. 28 is a bottom end view of the ice mold of FIG. 22. The broken line showings of portions of the ice mold in FIGS. 1-5, 7, 8-12, and 14 form no part of the respective embodiment of the ornamental design.
